United States Patent Office.

HENRY S. MAGRANE, OF HOBOKEN, NEW JERSEY.

Letters Patent No. 73,735, dated January 28, 1868.

IMPROVEMENT IN BUTTON-FASTENINGS.

The Schedule referred to in these Letters Patent and making part of the same.

TO ALL WHOM IT MAY CONCERN:

Be it known that I, HENRY S. MAGRANE, of Hoboken, in the county of Hudson, and State of New Jersey, have invented a new and improved Button-Fastener; and I do hereby declare that the following is a full, clear, and exact description thereof, which will enable others skilled in the art to make and use the same, reference being had to the accompanying drawings, forming part of this specification.

Figure 1 is a side view of my improved button-fastener.

Figure 2 shows the same partially inserted in the eye of a button.

Figure 3 shows its position when in use.

Similar letters of reference indicate corresponding parts.

My invention has for its object to furnish an improved fastener for ladies' cuff-buttons, vest-buttons, and similar uses, which may be easily inserted in the eye of the button, which will hold the button securely, which will not be liable to work itself out, and which, when inserted in the eye of the button, will lie closely against the surface of the garment; and it consists in a button-fastener, constructed in the form and manner herein-after more fully described.

A is the button-fastener, which is made of wire, the size of which will depend upon the size of the button, and the character of the garment to which it is to be secured. In forming the fastener, the wire of which it is to be formed is bent so as to form a loop, a^1 , in its middle part. The wires are then bent inward and again outward, as shown in fig. 1, to form a neck, a^2 , for the reception of the eye of the button. The ends of the wire are then bent inward, as shown in fig. 1, until their points meet or nearly meet, forming an acute angle. This forms the second loop, a^3 .

In using the fastener, the point of the fastener or ends of the wire are inserted in the eye of the button, and the fastener is then pushed into place, the wires taking the position shown in fig. 2, as they pass through the eye of the button, until the said eye has entered the neck a^2 , when the elasticity of the wire brings the fastener again into the form shown in fig. 1.

This construction makes the fastener very easy to be inserted and removed from the button in any situation, but it is especially convenient in attaching the central button, in putting up ladies' cuffs for market, entirely removing the difficulty which hitherto been experienced in attaching the said central button by means of any of the fasteners now in use.

I claim as new, and desire to secure by Letters Patent--

An improved button-fastener, made in substantially the form and manner herein shown and described, as a new article of manufacture.

The above specification of my invention signed by me, this 27th day of July, 1867.

HENRY S. MAGRANE.
